UNITED STATES PATENT OFFICE

132,460

DESIGN FOR A ROSARY DECADE RING

Capelle H. Damrell, Chicago, Ill., assignor of one-half to George T. Bullen, Chicago, Ill.

Application January 30, 1942, Serial No. 105,531

Term of patent 7 years

To all whom it may concern:

Be it known that I, Capelle H. Damrell, a citizen of the United States, residing at Chicago, in the county of Cook and State of Illinois, have invented a new, original, and ornamental Design for a Rosary Decade Ring, of which the following is a specification, reference being had to the accompanying drawing, forming part thereof.

I claim:

The ornamental design for a rosary decade ring, as shown.

CAPELLE H. DAMRELL.
